UNITED STATES PATENT OFFICE.

D. S. WAGENER, OF PENN YAN, NEW YORK.

GRAIN-SEPARATOR.

Specification of Letters Patent No. 26,311, dated November 29, 1859.

To all whom it may concern:

Be it known that I, D. S. WAGENER, of Penn Yan, Yates county, in the State of New York, have invented a new and useful 5 Improvement in Grain-Separators; and I do hereby declare that the following is a full and exact description thereof, reference being had to the accompanying drawings, and to the letters of reference marked thereon.

10 In the drawings; Figure 1 is a side view,—the dotted lines representing a longitudinal vertical section. Fig. 2 is a plan view. Fig. 3 represents the shoe and its spring. Fig. 4 shows the compound levers for raising or de-

15 pressing the cup.

In Fig. 1—*a* the casing or frame work. *b* the lower air chamber. *c* the upper air chamber. *d* the case of suction fan. *e* the suction fan. *e'* the fan in the lower air chamber. *g* the cone shaped cup into which the grain falls before it is distributed. *h* the pins which serve as guides, and which operate the cast iron eye *i*. *i* the cast iron case around the spindle and block, which are for 20 the purpose of giving to the grain a centrifugal and upward motion. *j* the levers (see Fig. 4) for operating the cup—It will be seen that one of these levers *j* is straight, while the other levers *j* are bent in such a 25 manner that the nuts *l* on their ends may be brought in contact with nut *l* on end of the first mentioned lever *j*;—the nuts *l* receive the end of thumbscrew lever *k* which operates this series of levers:—these levers *j* are 30 pivoted at *j'*, and are also pivoted to the lower ends of pins *h*—In operating this series of levers, the thumb-screw lever *k* (which passes through case *a*) elevates or depresses the rear ends of levers *j*, consequently depressing or elevating the farther ends which are pivoted to pins *h*, thus lowering or raising cup *g* for the purpose of increasing or diminishing the blast. *l* a pulley having a belt *l'* for driving suction fan *e*. 35 *m* flanges on the lower or under side of pulley *l*: these flanges *m* project below pulley *l* and just escape the bottom of upper air chamber;—they serve to catch the impurities and whirling them around thereby facilitate 40 their removal by the blast in the direction indicated by the arrow *z* (see post). *n* an annular guide for directing the grain into the cup *g*,—this guide *n* is a continuation of, or attachment to pulley *l*. *o* the power pulley: *o'* its belt. *p* the shaker:—this is polygonal in section, and hence in its revolu-

tions shakes the shoe which, by reason of springs, has a tendency to be close up to and parallel with one of the faces of this polygonal shaker. *r* is a double-cone sheath on the 60 spindle: the upper end of this sheath is made slightly concave the better to catch and throw off centrifugally the grain: I may find it convenient to add flanges to increase the force of this centrifugal action:—The 65 sheath is made doubly conical for the purpose of dividing the current of air from fan *e'* (which is in a line with the widest part of sheath) into two currents, the one passing down toward and into the eye of the stone, 70 and the other up through the descending grain or the whole current may pass up. *s* a rim surrounding the flanges *t* on cast iron rim *i*; the object of this rim or flange *s* is to direct the blast from the fan into a narrow 75 channel, forcing it to come over the upper edge of this rim, and down through the draft-steadying flanges *t* to the largest portion of sheath *r*. *t* flanges projecting from the under side of cast iron rim *i*. These 80 flanges or divisions serve to give steadiness to the current of air.

In Fig. 2 like letters designate like parts—*f* the receiver whence the air is drawn by the blast fan *e'*.

In Fig. 3 *q* is the shoe. *q'* the spring of shoe, which operates against shaker *p* of Fig. 1, and is to prevent noise.

In Fig. 4, letters similar to those of Fig. 1 are used.

In the operation of my invention the machine is put in motion, operating at the same time, both the blast and suction fans, or I may find it convenient sometimes to use only a blast or suction fan. The grain then 95 as it is discharged from the hopper, through guide rim *n*, into cup *g*, which by its shape gathers and drops it directly over and on head of sheath *r*, or a plate and case as its equivalent this distributor *r*, by its rapid rotation give to the falling grain a centrifugal force, throwing it up and out, in a circular form, within the circular case, the air then passing up around the distributor *r*, meets the grain at this point, and separates 100 from it all impurities, carrying them up into the upper air chamber whence they are removed by flanges on belt *l'*, to suction fan *e*, which discharges them at the opening indicated by arrow *z*, and the grain falls down 110 out of the machine cleansed from all impurities.

Having thus fully described my invention, what I claim as new and desire to secure by Letters Patent, is:

The case *i*, with flanges or divisions *t*, surrounding distributor or sheath *r*, or its equivalent, for distributing the grain in a circular form within said case, and separating the impurities from the grain at said

point, by means of a suction and blast fans, or by a suction or blast fan operating as described and the purposes set forth.

D. S. WAGENER.
